METHOD FOR HYDROCARBON OIL
TREATMENT

Lyman C. Huff, Chicago, Ill., assignor to Universal Oil Products Company, Chicago, Ill., a corporation of South Dakota

Application March 30, 1925, Serial No. 19,245
Renewed October 22, 1929

5 Claims. (Cl. 196—66)

This invention relates to method and apparatus for hydrocarbon oil treatment and refers more particularly to the idea of mixing the products from a cracking operation carried out under heat and super-atmospheric pressure in order to improve their quality and prevent excessive losses of the light ends.

The particular embodiment of the present invention is as follows: Oil is heated to a conversion temperature and discharged into an enlarged chamber, where vapors are released, these vapors being dephlegmated and the reflux condensate returned and mixed with the oil being heated. A substantial amount of the heated oil discharging into the enlarged chamber will remain unvaporized. The oil and vapors under treatment are maintained under a substantial super-atmospheric pressure.

The vapors leaving the dephlegmator and the unvaporized residue from the enlarged chamber are taken off as separate products and mixed together while still under heat and pressure. This mixture is then cooled while under substantially the same pressure.

The invention further resides in the idea of reheating the cooled mixture under pressure and then releasing the pressure and effecting distillation. The mixing of vapors and residue and the subsequent cooling of the mixture is done to prevent excessive losses of the lighter ends, as well as to improve the stability of the residuum which under the present invention will contain less settling. There will be less pitch forming and coke-like particles suspended in the residuum, which, of course, produces a much more desirable and marketable product which can be used for fuel.

The single figure in the drawing is a diagrammatic side elevational view of the apparatus. Referring in detail to the drawing, 1 designates the inlet line for the charging stock, which inlet line is controlled by valve 2 and discharges the raw oil into the closed coil 3. The closed coil 3 discharges the oil into the line 4 controlled by valves 5 and 6 and into the upper end of the dephlegmator 7. The purpose of passing the oil through the closed coil 3 is to preheat it, as hereinafter explained. If it is not desired to preheat the raw oil, the valves 2 and 5 may be closed and valve 8 in by-pass line 9 opened. The raw oil discharged into the dephlegmator will act as a cooling medium for the vapors, as will be hereinafter explained, and the unvaporized raw oil and reflux condensate will pass down through the reflux leg 10 controlled by valve 11

communicating with line 12, in which may be interposed the pump 13. This line 12 discharges the raw oil and reflux condensate into the inlet side of the continuous heating coil 14, which may be mounted in the side fired furnace 15 heated by means of the burners 16, the gases of combustion flowing downwardly countercurrent to the upward flow of the oil through the coils 14. The oil in its passage through the coil 14 will be heated to a conversion temperature and the heated oil discharged through the transfer line 17 controlled by valve 18 to the upper end of the enlarged reaction chamber 19, which may be insulated as shown at 20, and which is preferably externally unheated. This reaction chamber 19 is shown in the present instance as being disposed in a vertical plane, but it is understood, of course, that it may be disposed in any plane, for instance, a horizontal. Suitable manhole plates are provided for cleaning.

The lighter fractions of the heated oil will separate from the heavier fractions in the chamber 19 in the form of vapors and pass on through vapor outlet pipe 21 controlled by valve 22, being introduced to the lower portion of the dephlegmator 7. In their upper passage through the dephlegmator, these vapors are subjected to the baffling action of baffles, pans or bubble trays superimposed in the interior thereof, and the vapors are also physically subjected to the cooling effect of the raw oil introduced through the line 4. This cooling and baffling will cause the heavier ends of the vapors to condense out, returning with the raw oil through the reflux leg 10, as heretofore explained. The vapors remaining uncondensed after passing through the dephlegmator, pass out through the vapor outlet 23, in which is interposed valve 24, pressure gauge 25 and pyrometer 26. The unvaporized residue is withdrawn from the reaction chamber 19 through the residue draw-offs 27 controlled by valves 28, discharging into the residue draw-off header 29, in which is interposed valve 30 and pyrometer 31.

As a feature of the present invention, the vapors remaining uncondensed after dephlegmation are mixed with the unvaporized residue at the point 32, being introduced by means of the pipe connection 33 to the mixing chamber 34, where they are thoroughly mixed together. The mixer may take the form of a helicoid ribbon, such as shown at 35, although any other form of mixer may be utilized. The mixed product passes through the line 36, in which is interposed the pressure gauge 37, and may be passed

through the line 38, the valve 39 being opened, to the cooling coil 40, mounted in the box 41, from which box the cooled product is withdrawn through the line 42 controlled by valve 43.

- 5 As another method of operation, instead of cooling the product issuing from the line 36, the valve 39 may be closed and valve 44 in line 45 opened. The line 45 communicates by means of the line 46 and valve 47 with the heat inter-
10 changer 47'. The mixture passing through the heat interchanger is discharged through the line 48 controlled by valve 49, which line 48 communicates with the cooling coil 50 mounted in box 51, from which it may be withdrawn through the
15 line 52 and discharged to storage, valve 53 being opened.

Where it is desired to reheat the mixture to effect distillation thereof, the valve 53 is closed and the product issuing from pipe 52 is transferred to
20 the line 54, in which line is interposed the valve 55 and pressure gauge 56. This line 54 also passes through the heat interchanger and discharges through the line 57 controlled by valve 58, being introduced to the fractionating tower 59. Steam
25 may be introduced in the bottom of the fractionating tower to assist in the distillation and further heating of the mixture through the line 60 controlled by valve 61. Where it is not necessary to preheat the mixture at all, the valve 47 is closed
30 and valve 62 in connecting line 63 opened, causing the mixture to pass directly to the pipe 57 without passing through the preheater.

Distillation is effected in the tower 59, the vapors passing off through the vapor outlet 64 controlled by valve 65 communicating with condenser 66 in box 67, and the condensed product withdrawn through the line 68 controlled by valve 69 communicating with the receiver 70. The said receiver 70 may be equipped with the usual sight-
35 glass gauge 71, the gas relief line 72 controlled by valve 73 and liquid draw-off line 74 controlled by valve 75. The unvaporized bottoms may be withdrawn from the tower 59 through the line 76 controlled by valve 77.

45 It is not thought that any extensive explanation of the operation need be given in view of the detailed nature of the foregoing description. I am aware that heretofore vapors and residue discharging from a still or enlarged chamber have mixed together, but I believe I am the first to combine the reflux principle with the idea of mixing the vapors and unvaporized residue with a consequent beneficial effect. The tower 59 is in reality a vaporizer and stripping column. The pressure is preferably reduced slightly on both the vapors
50 and residue just prior to their mixing. As an illustration of the pressures which may be maintained throughout the plant, the pressure on the pressure gauge 25 may register 200 pounds; the pressure on the gauge 37 may register 175 pounds; the pressure on the gauge 56 may register 170 pounds, and the pressure on the gauge 56' may register 15 pounds. The oil passing through the heating coil 14 is heated to a temperature of say 750 to 950 F., more or less. It is pointed out that a certain amount of oil is continuously charged into the apparatus.

70 The slight reduction of pressure as evidenced by the difference in gauge readings between gauges 25 and 37 affords a means of control over the mixture being fed to the spiral mixer 34.

75 It has been ascertained in commercial practice that the quality of the products of a commercial cracking plan is impaired when the light and

heavy products are drawn off separately. In order to improve their quality and yet take advantage of the reflux principle in cracking the oil, it is advisable to bring the lighter ends and the heavier ends together while still under fairly high temperature and super-atmospheric pressure, mixing them thoroughly and cooling them under pressure before releasing the mixture from the system.

80 The arrangement shown also provides for cooling the mixture under pressure and heating it again before releasing it into the stripping column 59 for distilling the lighter gasoline ends.

I claim as my invention:

1. A method of hydrocarbon oil conversion, 90 consisting in heating the oil to a conversion temperature, discharging the heated oil into an enlarged chamber where substantial separation of lighter fractions in the form of vapors takes place, subjecting the vapors to dephlegmation, removing the uncondensed vapors after dephlegmation, returning and mixing reflux condensate from the dephlegmating zone with the oil being heated, separately withdrawing the unvaporized residue from the enlarged 100 chamber, maintaining a substantial superatmospheric pressure on the oil and vapors under treatment, mixing the vapors removed from the dephlegmating zone and heated residue from the enlarged chamber without substantially reducing 105 the pressure and cooling the mixture while still under pressure.

2. A process of hydrocarbon oil conversion comprising maintaining a body of oil under cracking conditions of temperature and pressure, subjecting vapors evolved from the oil to dephlegmation, removing uncondensed vapors from the dephlegmating zone, uniting reflux condensate separated from the vapors during dephlegmation with the oil undergoing treatment in the process, 110 separately withdrawing unvaporized residue from said body of oil, mixing uncondensed vapors removed after dephlegmation and heated residue from said body of oil while in a heated condition and under superatmospheric pressure, cooling the mixture while under pressure, thence admitting the mixture to a fractionating column wherein gasoline-like constituents only of the mixture are vaporized, maintaining a lower pressure in the fractionating column than maintained on said body of oil, and recovering the gasoline-like constituents vaporized in said fractionating column.

115 3. A method of cracking hydrocarbon oil which comprises heating the oil to a conversion temperature in a heating zone, discharging the heated oil into a reaction zone wherein separation of vapors and unvaporized oil takes place, removing the vapors and subjecting the same to dephlegmation, separately removing unvaporized oil 120 from said reaction zone, maintaining a superatmospheric pressure on the liquid and vapors undergoing treatment, combining the dephlegmated vapors with the withdrawn unvaporized oil under pressure, reducing the pressure on the resultant 125 mixture to effect a partial vaporization thereof, and condensing the evolved vapors.

130 4. A method of cracking hydrocarbon oil which comprises heating the oil to a conversion temperature in a heating zone, discharging the heated oil into a reaction zone wherein a separation of vapors and liquid oil takes place, removing the vapors and subjecting the same to dephlegmation to condense the heavier insufficiently cracked fractions, returning the condensed heavier frac- 135

tions to said heating zone for retreatment in the process, separately removing unvaporized oil from said reaction zone, combining the dephlegmated vapors with the removed unvaporized oil under pressure, reducing the pressure on the resultant mixture to effect a partial vaporization thereof, and condensing the evolved vapors.

5 5. A process for pyrolysis of hydrocarbon oil comprising the steps of digesting a body of heat-

ed oil under conditions permitting vaporization, condensing a portion of the vapors evolved, withdrawing a stream of oil from said body, discharging said stream of oil without substantial loss of heat into a separation zone in intimate contact with the uncondensed portion of said vapor, and fractionating the mixture in said separation zone.
